J. HUMPHREYS

TRACK LINER

Filed July 23, 1925

Inventor

J. Humphreys
Watson E. Coleman

Attorney

UNITED STATES PATENT OFFICE.

JOHN HUMPHREYS, OF CASPER, WYOMING.

TRACK LINER.

Application filed July 23, 1925. Serial No. 45,637.

To all whom it may concern:

Be it known that I, JOHN HUMPHREYS, a citizen of the United States, residing at Casper, in the county of Natrona and State of Wyoming, have invented certain new and useful Improvements in Track Liners, of which the following is a specification, reference being had to the accompanying drawings.

10 This invention relates to certain improvements in track liners and has relation more particularly to a device of this general character employing a single throw lever, and it is an object of the invention to provide a 15 device of this kind which operates to exert a pull upon the track in contradistinction to a push or throw upon the track.

Another object of the invention is to provide a device of this general character which 20 operates initially to slightly raise the rail and the adjacent ties to facilitate the requisite movement of the rail into proper line.

25 A further object of the invention is to provide a device of this kind employing a rock lever engageable with an edge of the base of a rail and wherein such engagement may be had at selective points on the lever to provide for different speeds and power.

30 The invention consists in the details of construction and in the combination and arrangement of the several parts of my improved track liner whereby certain important advantages are attained and the device 35 rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:—

45 Figure 1 is a view partly in longitudinal section and partly in elevation of a track liner constructed in accordance with an embodiment of my invention, the co-acting rail being diagrammatically indicated by broken 50 lines;

Figure 2 is a view in top plan of the structure as illustrated in Figure 1;

Figure 3 is a sectional view taken substantially on the line 3—3 of Figure 1.

55 As disclosed in the accompanying draw-

ings, B denotes a base plate of requisite dimensions and which has depending from its under surface the transversely disposed flanges 1, said flanges being spaced apart lengthwise of the plate B. These flanges are 60 adapted to penetrate the ballast or bed of a trackway to maintain the same in substantially a fixed position during a working operation. In the event such bed or ballast should be too soft spikes or the like are 65 adapted to be driven therein through the transversely spaced openings 2 provided in the outer end portion of the plate B.

The central portion of the plate B is provided entirely therewith a rack 3 the 70 teeth of which being of a ratchet type disposed toward the outer end of the plate B, said teeth being also preferably disposed below the upper surface of the plate. Interlocking with the rack 3 are the teeth 4 provided along the under surface of the intermediate or base wall 5 of a channel member M whereby the member M may be selectively positioned upon the plate B and held against movement toward the inner end of the plate. 80 The wall 5 has disposed therethrough in its central portion a longitudinally directed slot 6 in which is arranged the flattened upper portion a of a bolt 7, said bolt 7 having its lower part directed through an opening 8 disposed through the plate B at a predetermined point intermediate the ends of the rack 3. The head 9 of the bolt 7 overlies the upper surface of the wall 5 of the member M for contact therewith at opposite sides 85 of the slot 6 and engaged with the lower or free end of the bolt 7 for contact with the under surface of the plate B is a nut 10. The bolt 7 and its coating nut 10 provide means whereby the member M is effectively 90 locked or held in its selective position upon the plate B. The flattened portion a of the bolt 7 is relatively wide and provides means to assure the applied member M to be held 95 against lateral displacement with respect to the rack 3 and which would otherwise be liable to occur if said member M was free to rotate about the bolt 7.

Pivotedly supported, as at 11, between the inner portions of the side walls 12 of the member M is an upstanding lever 14 the inner face of which being provided thereacross with the transversely disposed grooves or channels 15 rounded in cross section and which are adapted, during a working opera- 105 110

tion, to engage an edge of the base of a rail R when aligning, said rounded formation of the grooves or channels 15 permitting a ready release of the rail from the lever 14. 5 As herein disclosed, I employ three grooves or channels 15 which give three powers and three speeds in operation.

The pivoted end portion of the lever 14 is continued by an elongated arm 16 substantially at right angles thereto and disposed toward the outer end of the plate B. The free end portion of the arm 16 is bifurcated to provide a kerf 17 in which is received an end portion of a rigid link 18 pivotally connected, as at 19, to said outer end portion of said arm 16. The opposite end portion of the link 18 is received with a mortise or slot 20 provided in the pivoted end portion of a second lever 21, said end portion of the link 18 being pivotally connected, as at 22, to said lever 21. The lever 21 is pivotally supported, as at 23, between the outer end portions of the side flanges 12 of the member M and the outer end of the lever 21 is provided with a socket member 24 adapted to have operatively engaged therewith a suitable operating handle. The free end portion of the arm 16 overlies the pivoted end portion of the lever 21 and the pivotal mounting 23 for said lever 21 is preferably at a point below the pivotal connection 11 for the lever 14 so that as the lever 21 moves downwardly the lever 14 will move upwardly and vice versa.

35 In practice, the member M is moved toward the inner end of the plate B substantially as far as permitted by the bolt 7 and the lever 21 is raised in order to lower the lever 14. The device is then placed below the rail R and an edge of the base flange of such rail engaged within a notch 15 of the lever 14. The lever 21 is then forced downwardly and this first operation or stroke causes the plate B through the medium of the flanges 1 to effectively engage or grip the road bed or ballast. The lever 21 is then raised and lowered until the lever 14 has effected the desired lining of the rail. The first movement or operation of the lever 14 serves to loosen the adjacent ties from the road bed or ballast to a slight extent and thereby making it easier to move the rail but does not raise enough to allow the ballast to run under the ties and hold 55 the track out of surface.

It is to be particularly noted that my improved liner pulls the track in contradistinction to the general practice of pushing or throwing the same.

60 From the foregoing description it is thought to be obvious that a track liner constructed in accordance with my invention is particularly well adapted for use by reason of the convenience and facility with which it may be assembled and operated, and it

will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A track liner comprising, in combination, a base plate provided with a rack on its upper surface, a channel member having its base wall provided with teeth meshing with the rack of the base plate, said base wall of the member having a slot disposed in the same general direction as the rack of the base plate, a bolt disposed through the base plate and the slot of the member, the portion of the bolt within the slot being flattened to hold the member against turning movement about the bolt, a rail engaging lever pivotally supported by the member, and means for exerting pull upon said lever.

2. A track liner comprising, in combination, a base plate provided with a rack on its upper surface, a channel member having its base wall provided with teeth meshing with the rack of the base plate, said base wall of the member having a slot disposed in the same general direction as the rack of the base plate, a bolt disposed through the base plate and the slot of the member, the portion of the bolt within the slot being flattened to hold the member against turning movement about the bolt, a rail engaging lever pivotally supported by the member, a second lever pivotally engaged with the member, and a link operatively connecting the two levers to exert pull upon the first lever upon movement of the second lever in one direction.

3. A track liner comprising, in combination, a base plate provided with a rack on its upper surface, a channel member having its base wall provided with teeth meshing with the rack of the base plate, said base wall of the member having a slot disposed in the same general direction as the rack of the base plate, a bolt disposed through the base plate and the slot of the member, the portion of the bolt within the slot being flattened to hold the member against turning movement about the bolt, a rail engaging lever pivotally supported by the member, and means for exerting pull upon said lever, said base plate being provided with anchoring means.

4. A track liner comprising, in combination, a base plate provided with a rack on its upper surface, a channel member having its base wall provided with teeth meshing with the rack of the base plate, said base wall of the member having a slot disposed in the same general direction as the rack of the base plate, a bolt disposed through the base plate and the slot of the member, the portion of the bolt within the slot being flattened to hold the member against turning movement about the bolt, a rail engaging lever pivotally supported by the member, and means for exerting pull upon said lever, said base plate being provided with anchoring means.

base plate and the slot of the member, the portion of the bolt within the slot being flattened to hold the member against turning movement about the bolt, a rail engaging lever pivotally supported by the member, and means for exerting pull upon said lever, the working face of the lever being

provided with transversely disposed grooves to selectively receive an edge of the base flange of a rail.

In testimony whereof I hereunto affix my signature.

JOHN HUMPHREYS.
